(57) **CLAIM**

The ornamental design for a vacuum cleaner handle, as shown and described.

DESCRIPTION

FIG. 1 is a side elevational view of a vacuum cleaner handle showing our new design, the opposite side being a mirror image;

FIG. 2 is a front elevational view thereof;

FIG. 3 is a rear elevational view thereof;

FIG. 4 is a top plan view thereof; and,

FIG. 5 is a bottom plan view thereof.

The details shown in broken lines in all views are for illustrative purposes only and form no part of the claimed design.
